UNITED STATES PATENT OFFICE

ABRAM C. WISNER, OF JACKSON, MICHIGAN, ASSIGNOR TO REYNOLDS SPRING COMPANY, OF JACKSON, MICHIGAN, A CORPORATION OF MICHIGAN

CUSHION SPRING CONSTRUCTION

Application filed March 26, 1928. Serial No. 264,916.

The present invention pertains to a novel cushion spring construction of the type used in building automobile seats, mattresses, chair seats and the like.

5 A certain class of such spring structures consists of a series of axially elongated coil springs supported on a suitable base in spaced relation to each other and covered with upholstery material. Due to the spacing among 10 these springs, there remain substantial areas in which the upholstery material is unsupported. For the same reason the load placed upon the structure is likewise unsupported at definite areas, and the result is undue 15 strain, distortion and wear of the upholstery material at these unsupported areas.

The present invention aims to avoid such unsupported areas by the provision of a flat spring structure or mat placed upon the elongated coil springs. The top structure consists, briefly, of a number of flat coil springs 20 clipped together and also to the top coils of the elongated springs and to the frame of the structure. The flat springs are manifestly 25 positioned in such a manner as to overlie and partly cover the spaces occurring between and within the elongated springs.

The invention is fully disclosed by way of example in the following description and in 30 the accompanying drawings, in which—

Figure 1 is a plan view of a construction built according to the invention;

Fig. 2 is a transverse section thereof;

Fig. 3 is a detail section thereof on the line 35 3—3 of Figure 2; and

Fig. 4 is a plan view of a modified construction.

Reference to these views will now be made by use of like characters which are employed 40 to designate corresponding parts throughout.

The construction shown in Figures 1, 2 and 3 include a wire base frame 1 and a similar upper frame 2 between which are disposed a series of double conical spiral springs 3.

45 These springs have their lower ends clipped

as at 4 to the base frame 1 wherever contiguous thereto and are further secured by clips 5 to tie bars 6 laid across the base frame. The upper ends of the springs 3 are similarly clipped as at 7 to the upper frame 2 wherever 50 contiguous thereto.

It will be seen that the springs 3 are spaced considerably from each other, and it is one of the objects of the invention to provide load sustaining members in these spaces as already indicated. Accordingly I form a top structure consisting of flat springs 8 clipped together as at 9 in a common plane and laid upon the tops of the springs 3. The axes of the flat springs are disposed substantially in the centers of the spaces defined by the springs 3, and the flat springs are of such size as to extend substantially over the tops of the elongated springs as clearly shown in Figure 1. The outer ends 10 of the flat 60 springs are brought into tangency with the sides of the frame 2 and are secured thereto by clips 11.

The innermost coils of the flat springs 8 lie tangent to the outermost coils of the surrounding springs 3 and are likewise secured thereto by clips 12.

In the modification shown in Figure 4 the top structure has a different relation to the centers of the spaces between the elongated coil springs 3'. In this case a mat is formed of flat coil springs 13 clipped together at 14 and adapted to lie upon the springs 3'. In the embodiment shown there are five flat springs in the length occupied by four elongated springs, so that the flat springs not only cover the spaces between the elongated springs but also provide a bearing surface in the open spaces formed by the uppermost coils of the elongated springs. The flat springs are 85 clipped as at 15 to the upper frame 2 where contiguous thereto and also to the uppermost coils of the springs 3', as at 16, wherever substantially tangential thereto.

It will now be apparent that the upper 90

- structure composed of the flat springs provides considerable bearing surface in the spaces between and within the elongated springs, so that the load upon the structure 5 is evenly distributed over the upper surface rather than confined merely to the points where the upholstery material contacts with the uppermost convolutions of the elongated springs.
- 10 Although specific embodiments of the invention have been illustrated and described, it will be understood that various alterations in the details of construction may be made without departing from the scope of the invention as indicated by the appended claims.

What I claim is:—

1. In a spring construction comprising axially elongated coil springs having their tops in a common plane, the combination of a 20 separate top structure covering a plurality of said spring tops and consisting of flat coil springs directly connected to each other, said flat coil springs overlapping and resting upon the tops of said elongated springs.
2. In a spring construction comprising axially elongated coil springs having their tops in a common plane, the combination of a 25 separate top structure consisting of flat coil springs interconnected in mutually tangential relation and laid upon said tops.
3. In a spring construction comprising axially elongated coil springs having their tops in a common plane, the combination of a 30 separate top structure consisting of flat coil springs directly connected to each other, laid upon and overlapping said tops and clipped thereto.
4. In a spring construction comprising axially elongated coil springs having their tops in a common plane, the combination of a top 35 structure consisting of flat coil springs laid upon said tops and clipped thereto and to each other.
5. In a spring construction comprising axially elongated coil springs having their tops in a common plane, certain of said tops being spaced from each other, the combination of a top structure consisting of flat coil 40 springs clipped together and laid upon said elongated springs and having their axes substantially in the centers of the spaces defined by said elongated springs, each flat spring extending over the elongated springs around its center.
6. In a spring construction comprising axially elongated coil springs having their tops in a common plane, certain of said tops being spaced from each other, the combination of a top structure consisting of flat coil 45 springs clipped upon said elongated springs and having their axes substantially in the centers of the spaces defined by said elongated springs, each flat spring extending over the elongated springs around its center.
7. In a spring construction comprising ax-

ially elongated coil springs having their tops in a common plane, certain of said tops being spaced from each other, the combination of a top structure consisting of flat coil springs clipped together and upon said elongated springs and having their axes substantially in the centers of the spaces defined by said elongated springs, each flat spring extending over the elongated springs around its center.

In testimony whereof I affix my signature.

ABRAM C. WISNER.
